JAMES G. NOLEN, OF NEW YORK, N. Y., ASSIGNEE TO ROBERT L. MCELROY, OF CHARLOTTESVILLE, VIRGINIA

TRAPPED KEY SIGNAL TRANSMITTER AND VALVE CONTROL MEANS

Application filed November 11, 1925. Serial No. 62,435.

This invention relates to key-controlled electrical signal transmitters and key-controlled devices for supervising systems.

One object of the invention is to provide apparatuses of this kind by means of which an attendant may be compelled to transmit a signal each time a device, for instance, the main valve of a sprinkler system is operated.

Another object of the invention is to provide an apparatus of this kind which may be placed a distance from the apparatus controlled without any conducting wires or other material connection between the two.

Other objects of the invention are to provide an improved key-controlled and key-controlling signal transmitter and to provide a key-controlled device adapted for trapping the key therein under predetermined known circumstances.

Other objects of the invention are to improve generally the simplicity and efficiency of such devices and to provide devices or apparatuses of this kind which are reliable, durable and economical to manufacture.

Still other objects of the invention will appear as the description proceeds; and while herein details of the invention are described, the invention is not limited to these since many and various changes may be made without departing from the scope of the invention as claimed.

The inventive features for the accomplishment of these and other objects are shown herein in connection with an improved control apparatus which, briefly stated, includes a sprinkler system having a normally open main valve or water gate having a key-controlled lock for locking the valve in normally open position, said lock releasing the key when said valve is locked in said normally open position and trapping the key in the lock when said valve is not in said normal position; and a transmitter for sending signals to a supervisory station or office and adapted to receive said key for trapping the key in the transmitter and sending one kind of signal showing that the key is trapped, and with means for releasing the key and sending another kind of signal as the key is released.

Thus when a signal has been received showing that the key has been trapped in the transmitter, but no signal has yet been received showing that the key has been released, it is known at the office that the key is trapped in the transmitter and, therefore, that the valve is locked open, since the key cannot be released from the lock except when the valve is locked open.

When for any reason, as for instance, after a fire, it is necessary to close the valve, the key cannot be removed from the transmitter without sending a signal that it is being released. Thus the office is advised whenever the key is removed to close the valve, and again when the valve has been locked open and the key replaced in the transmitter.

In the accompanying drawings, showing by way of example, two of many possible embodiments of the invention,

Fig. 1 is a fragmental side elevation showing a sprinkler system with the key-controlled lock applied thereto;

Fig. 2 is a central vertical sectional view, partly in elevation, showing the valve rod and wheel and the lock therefor;

Fig. 3 is a side elevation, partly in central vertical section showing one form of the transmitter;

Fig. 4 is a fragmental front elevation, partly in section on the line 4—4 of Fig. 3, showing the transmitter control means;

Fig. 5 is a fragmental front elevation, partly in section on the line 5—5 of Fig. 3, showing the key-receiving means of the transmitter;

Fig. 6 is an exterior front elevation of the transmitter; and

Fig. 7 is a front elevation showing another form of transmitter control means.

My transmitter and valve control means are herein shown, by way of example, in connection with a sprinkler system including a supply main 10, a riser 11, service pipes 12 having sprinkler heads 13 and a main water valve or gate 14 having a seat 15 on which is mounted a bracket 17 having a hub 18 (Fig. 2) having a boss 19 on which is received a valve wheel 20 having a hub 22.

having a tapped opening 23 alined with a smooth central bore 24 of said hub 18, and a bottom recess 25 fitting on said boss 19. A split face plate 27 secured on the lower 5 face of the hub 22 of the wheel engages under a flange 28 of the boss to hold said wheel against removal. A threaded operating rod 30 connected to the movable member or gate of the valve is received in said central bore 10 24 and opening 23.

The valve control means

Said threaded rod is provided with a recess 31 alined with a radial bore 32 of the 15 bracket, when the rod 30 is in normal open position.

A lock housing 35 secured fast on said bracket by means of an extension 36 and screws 37 carries a bolt 38 slidable through 20 said housing and radial bore 32 and into said recess 31 and having an intermediate lug 39 engageable in a notch 40 of said plate 27.

A pin 45 fast across the housing is received 25 in a longitudinal slot 46 of the bolt; and tumblers 47 pivotally mounted on the bolt and downwardly pressed by springs 48 have usual locking slots 49 receiving said pin.

Said housing is provided with an upward 30 35 ly inclined key hole 50 positioned to receive a key 51 in position to engage in an inverted V-shaped notch 51' in the lower edge of the bolt to unlock the bolt and raise the tumblers to permit the key and bolt to move the 35 key to unlocking position with the key out of register with the keyhole.

The keyhole is too near to the adjacent 40 walls 52 and 53 of the housing to permit a complete rotation of the key, whereby when 40 the key is in unlocking position in the lock and said screw rod 30 is moved to carry the recess 31 out of register with the bolt 32, said bolt and key are held in unlocking position and the key is trapped in the lock.

45 In view of the above, it will be seen that only when the rod 30 is in open position may the key be removed to wind up and be trapped in the transmitter to permit sending a signal to the central station to show that said main 50 valve is locked in open position.

The transmitter

The transmitter of Figs. 3 to 6 is mounted on a porcelain base 60 (Fig. 3) and includes 55 a clockwork 61 similar to that shown in my U. S. Patent No. 1,082,606, issued Dec. 30, 1913, for a supervisory alarm system. As herein shown this clockwork comprises a pair of pillar plates 62, 63, posts 64, 65 separating the plates, a main winding arbor 66 and a clock spring 67 having one end secured to the arbor 66 and the other anchored to one 60 of the posts 65. A main drive gear 68 loose on the arbor and an escapement wheel 69 65 engaging a pallet 70 are connected by inter-

mediate gears 71 on an intermediate shaft 72.

The clockwork as above described is almost identical with that of the patent except that the spring is secured to the post and a pawl and ratchet mechanism 73, 74 is interposed between the arbor and drive gear 68, whereby the clockwork may be wound while not running and whereby the arbor must be rotated as the clockwork runs down, for a reason to be set forth.

A toothed signal transmitting wheel 80 mounted upon the intermediate shaft having six times the speed of the winding arbor, and a make and break jack 81 mounted on a bracket 82 on the clockwork and having a pen 85 engaging said transmitting wheel are also the same as in said patent, and operate in the same way for sending a signal to a central supervisory station.

A transmitter housing 85 is mounted on said base over said clockwork and is provided in its outer wall 86 with a downwardly pointing keyhole 87 receiving the extended end 87' of the winding arbor 66; and inner and outer spaced plates 88 and 89 between and spaced from said clockwork and outer wall provide an inner transmitter control compartment 90 and a key control compartment 91.

The key receiving means

A key receiving disk 95 in the key control compartment fast on the arbor adjacent to said outer plate 89 carries a movable ward 96 adapted to receive a cut 97 in the key bit 98 of the key 51, and a recess 99 outside of the ward adapted to receive a projection 100 near the end of the bit, whereby the disk and arbor may be rotated and the spring wound up. A fixed ward 101 on said outer wall 86 is adapted to be received in an outer edge cut 102 of the bit. The wards 96 and 101 may be omitted if desired.

A pivot pin 105 (Fig. 5) mounted on said outer plate near the periphery of said disk and the path of the end of the key bit carries a plurality of tumblers 106 intermediate fulcrumed on said pin and provided at the forward ends with forwardly opening slots 107 and engageable at the rear ends 108 by the key bit to aline said slots just before the limit of movement of the key bit about 180 degrees from the keyhole, whereby said slots may receive a projection 110 thereby to permit said key to reach said limit and to prevent the key and disk from reaching said limit when the slots are not thus alined. An upstanding bracket plate 111 mounted on said outer plate carries flat springs 112 pressing upon said tumblers respectively for pressing said rear ends 108 into the path of said bit and into engagement with said movable ward, thereby yieldably holding said slots 107 normally out of alinement.

6013 *The transmitter control means*

A vibratory arm 115 on the pallet staff 116 carries a weight 117 engageable by an active arm 118 of a dog 119 (Fig. 4) frictionally pivotally mounted on a base washer 120 and provided with a motive arm 121 disposed over the edge of a control disk 122 fast on said arbor and carrying a releasing pin 123 on the margin of said disk adapted to engage said motive arm 121 when the key moves to the position 98b about 180 degrees from the keyhole position 98a thereby to remove said active arm 118 from the path of said weight to release the clockwork to cause the key to move back toward the keyhole and to cause the sending of two signals by the signal wheel 80.

20 *The key trapping means*

A yieldable lever 125 pivoted as at 126 on said inner plate is provided with a stop arm 127 adapted to move into the path of said weight 117 and with a cam arm 128 having a cam end 129 pressed by the spring 130 against the periphery of the control disk 122, thereby to hold said stop arm 127 from said path. Said end 129 is adapted to move, under the action of the spring 127, into a peripheral notch 131a of the disk 122 after the key 51 has moved about 120 degrees and two signals have been sent, thereby to move said stop arm 127 into said path and stop the clockwork with the key held trapped at the position 98c about 60 degrees from the keyhole, said two signals indicating at the central office that the key is thus trapped.

30 *The key releasing means*

A releasing arm 133 fast on said yieldable lever with its outer end 134 projecting through the housing may be manipulated to remove said stop arm 127 from said path to permit the key bit to move to register with the keyhole, where it may be removed, and to permit the clockwork to send another signal to show that the key has been released.

40 A stop pin 135 on said control disk about 180 degrees from the releasing pin 123 is adapted to engage said motive arm 121 to shift said active arm 118 into said path to stop the clockwork when the key bit reaches releasing position 98a in registration with the keyhole.

50 *Transmitter control means of Fig. 7*

In Fig. 7 is shown a form of invention adapted for use with the transmitter of the above named patent with very slight change, and with the addition of a very small number of parts.

60 In this form of the invention, the clockwork and a signal transmitter are similar to that of Fig. 3 except that the plates 88 and 89 and the parts carried thereby are omitted and the winding and unwinding arbor 166

has a squared end 167, and the clockwork has a vibrating member 168 on the pallet staff in addition to the weight 169 on the pallet itself. The housing 170 over this transmitter is provided with a horizontally disposed keyhole 70 171 alined with said squared end 167 and adapted to receive a key having a squared hole 172 adapted to be received on said squared end.

A pivoted dog 175 pivotally mounted direct 75 on the pillar plate 63 provided with an active arm 176 having bifurcations 177 one of which is normally in the path of a downturned end 178 of said member 168, and a motive arm 180 adapted to be engaged by said bit 98 when 80 the key reaches its inner limit of rotation 98b, thereby to remove said bifurcations of the active arm from said path to permit the transmitter to send a signal. Tumblers 183 pivoted on said motive arm 180 are provided with 85 slots 184 and are engageable by the bit to position said slots in position to receive a pin 185 fixed on said clockwork to permit the dog to pivot.

90 *Key trapping and releasing means*

A yieldable lever 185 intermediately pivoted as at 186 has a stop arm 187 adapted to move into the path of said end 178 and a spring 189 having a cam end 190 adapted 95 to be engaged by the bit 98 after said signal has been sent, thereby to move said stop arm 187 against the action of the weak spring 191 into said path and stop the clockwork with the key held trapped at the position 98c (Fig. 100 7) out of registration with the keyhole 171. A releasing pin 193 slidable in a block 194 mounted on the casing wall is adapted to press upon the lever 185 to remove the stop arm 187 from said path to permit the key to move the 105 clockwork to send another signal and to move the key to releasing position in registration with the keyhole.

A restoring arm 197 on said dog is adapted 110 to be engaged by said bit 98 to move said motive arm 176 back into said path to stop the clockwork when the key reaches releasing position 98a in registration with the keyhole.

Wards 198 and 199 fast on the pillar plate and casing respectively receive the cuts 97 115 and 102 of the key.

120 *Operation of the system*

Normally the valve is locked open and the key is trapped in the transmitter. When the key is removed from the transmitter to close the gate, a signal is automatically sent to the office advising of this fact, and when the key is returned to the transmitter a signal is again sent.

125 *Operation of the valve control*

The valve is normally open with the parts as shown in Fig. 2 except that the key is removed and locked in the transmitter. When 130

the valve must be closed, the key is taken from the transmitter, as will be explained, inserted in the keyhole 50 (Fig. 2), and turned back about 90 degrees, thus raising the tumblers, 5 carrying the bolts and tumblers back and leaving the key in the lock, as the key cannot make a complete rotation.

This movement withdraws the bolt 32 from the recess 31, and the lug 39 from the notch 10 40, permitting the wheel to be rotated and the recess 31 to move out of alinement with the bolt thus preventing forward movement 15 of the bolt and key and preventing removal of the key. Thus when the valve is in closed position, the key must be in the lock and cannot be in the transmitter.

When the valve may again be opened, the wheel is rotated to raise the rod 30 and to bring the recess 31 and notch 40 into registration 20 with the bolt 32 and lug 39 respectively, permitting the key and bolt to be moved forward to lock the rod and wheel and to permit the key to be removed and replaced in the transmitter.

25 *Operation of the transmitter controller means of Figs. 3 to 6*

As stated, the main valve of the sprinkler is normally open and all parts of the valve 30 operating means are as shown in Fig. 2, except that the key has been removed, and is trapped in the transmitter in the position of 98c of Figs. 4 and 5.

In this position of the key, the notch 131, 35 the cam end 121, the stop arm 127 and the active arm 118 have the positions of the dotted lines of Fig. 4, whereby the weight 117 is held from vibration by the stop arm 127, but is not interfered with by the arm 118.

40 *Releasing the key*

If for any reason, as for instance, just after 45 a fire, it is necessary to close the valve, the supervisory station or office must be informed, and the attendant is compelled to inform the office before he closes the valve, since it is not possible to remove the key from the transmitter without sending a signal.

When it is necessary to remove the key 50 from the transmitter, the attendant merely presses upon the projecting end 134 (Fig. 4) of the releasing arm, thus moving the stop arm 127 from the portion of the dotted lines in path of the weight 117 to the position of the full lines outside of said path, thus releasing the clockwork and permitting the arbor and key to move from the position 98c to 55 98a, the signal transmitting wheel 80 making one rotation, since it has six times the speed of the arbor, and sending one signal to the office showing that the key has moved to the position 98a and may be removed for closing the valve.

When the key reaches the position 98a, 60 the pin 135 engages the motive arm 121 and

moves the arms 118 and 121 from the position of the dotted lines to the position of the solid lines, thus stopping the clockwork with the key in the position of 98a.

The key may now be removed for closing 70 the valve as will be explained. The attendant is required to reopen the valve as soon as possible, and as soon as the valve has been reopened, he will wish to advise the office of this fact, which he does by reinserting and 75 trapping the key.

Inserting and trapping the key

The key is inserted in the keyhole, with the projection 100 (Fig. 3) engaging in the 80 recess 99. The key is then moved from the position 98a to the position 98b, thus moving the notch from the position 131a past the position 131c to the position 131b, whereby the stop arm 127 is held in the position of the 85 solid lines, while the pin 123 (Fig. 4) moves into engagement with the motive arm 121, thus moving the active arm 118 to the position of the dotted lines, releasing the clockwork, permitting the movement of the key to 90 the position 98c, the notch to the position 131c and the stop arm 127 to the position of the dotted lines under the action of the spring 130, thus trapping the key. During this movement the signal transmitting wheel rotates twice sending two signals, thus showing 95 that the key is trapped, and that the valve is locked open.

Operation of the tumblers

As the key moves to the position of 98b, the key bit engages the ends 108 (Fig. 5) of the tumblers, and if the right key is used, the slots 107 become alined for the reception of the projection 110. If a false key is used, the slots 107 will not be alined for the reception of the projection 110 and the pin 123 (Fig. 4) cannot move far enough to cause the arm 118 to release the clockwork. As the arbor and key will then be held against backward 105 rotation by the pawl and ratchet 73, 74 (Fig. 3, the false key will be trapped and no signal will be sent. As it will be noticed at the office that no signal has been received, investigation will be made and the attempt to use a 110 false key will be disclosed.

Obviously either the wards or the tumblers or both may be omitted if desired.

Operation of the control means of Fig. 7

The key is normally trapped in the transmitter in the position of 98c (Fig. 7) with the cam end 190 and the stop arm 187 in the position of the dotted lines. To release the key, the attendant presses inwardly the pin 193, thus moving the lever 185 and the arm 187 against the action of the spring 189 to the position of the solid lines, the cam end 190 remaining substantially in the position of the dotted lines. The pin 193 is thus held in 120 125 130

until the clockwork, which is thus released, moves the key bit past the cam end 190 until it comes into registration with the keyhole and against the restoring arm 197, thus moving one of the prongs 177 into the path of the downturned end 178 to stop the clockwork after the latter has caused the sending of one signal to show that the key has been moved to releasing position to be removed.

10 After the key has been used, it is reinserted in the keyhole 171 and the bit moved past the position 98c to near the position 98b where it encounters the tumblers 183 and positions the slots 183 to receive the pin 185 as the key 15 bit engages the motive arm 180 to position the prongs 177 out of the path of the downturned end 178.

This releases the clockwork and permits the sending of two signals as the bit moves to 20 the position 98c and engages the cam end 190 to move said stop arm 187 into said path to stop the clockwork with the key trapped in the position 98c.

With either of the transmitters, the key 25 must be removed from the transmitter and send one signal whenever there is any trouble requiring the closing of the valve, and as the key is returned to the transmitter it sends two signals when the trouble is checked, the office 30 will consider one signal as the "trouble" signal and the two signals as the "check" signal.

I claim as my invention:

1. In combination, a key-controlled means for releasing the key of said means when said 35 means is locked in one position and trapping the key when said means is not in said position; and signal means controlled by the key for trapping the key and giving one kind of signal when the key is trapped and another 40 kind of signal when the key is released.

2. In combination, a sprinkler system; a main valve for said system; a key-controlled lock for locking said valve in one position; said lock including means releasing the key 45 when said valve is locked in said position and trapping the key in the lock when said valve is not in said position; and means for giving a signal adapted to receive said key and adapted to trap the key in the signal means 50 and to send a signal when the key is trapped, and adapted to release the key and send another signal when the key is released.

3. In combination, a valve; a key-controlled lock for locking said valve in one position; said lock including means releasing the key when said valve is locked in said position and trapping the key in the lock when said means is not in said position; and signal means for giving a signal adapted to receive 60 said key and adapted to trap the key in the signal means and to give a signal when the key is trapped, and adapted to release the key and give another signal when the key is released.

4. In combination, a control means; a key-

controlled lock for locking said means in one position; said lock including means releasing the key when said means is locked in said position and trapping the key in the lock when said means is not in said position; and signal means for giving a signal adapted to receive said key and adapted to trap the key in the signal means and to send one kind of message when the key is trapped, and adapted to release the key and send another kind of message when the key is released. 70 75

5. In combination, a sprinkler system having a valve; a key; a key-controlled lock for locking the valve in normally open position; said lock including means releasing the key when said valve is locked in said normally open position and trapping the key in the lock when said valve is not in said normal position; and a transmitter for sending a message and adapted to receive said key; said transmitter being provided with means for trapping the key in the transmitter and sending one kind of signal when the key is trapped, and with means forleasing the key and sending another kind of signal when the key is released. 80 85 90

6. In combination, a signal transmitter comprising a main winding arbor, a spring having its inner end secured to the arbor and having fixed anchorage at the outer end; a main drive gear loose on the arbor, a vibrating member and a pawl and ratchet mechanism between the arbor and drive gear; a housing over said transmitter provided with a keyhole; a key-receiving disk fast on the arbor provided with a recess to receive a projection on the key; tumblers provided with slots, and engageable by the bit to position said slots; a projection on said disk adapted to enter said slots to permit said key 100 to reach its said limit of movement; and control means engageable with said vibrating member. 105

7. In combination, a signal transmitter comprising a winding and unwinding arbor, and a vibrating member; a housing for said transmitter provided with a keyhole in its outer wall; a key receiving disk control compartment fast on the arbor provided with a movable ward adapted to receive a cut in the key bit, and a key receiving recess outside of the ward adapted to receive a projection near the end of the bit, whereby the arbor may be wound up; a fixed ward on said outer wall adapted to be received in an outer edge out of the bit; and means actuated by the arbor adapted when the key reaches its inner limit to cause said transmitter to signal and to stop the transmitter when the key reaches releasing position. 110 115 120

8. In combination, a signal transmitter comprising a winding and unwinding arbor, and a vibrating member; a housing for said transmitter provided with a keyhole; a key-receiving part fast on the arbor; a disk on 125 130

said arbor provided with a notch; a pivoted dog normally in the path of said member; a releasing pin on the disk adapted to engage said dog when the key reaches its inner limit 5 of rotation, thereby to remove said dog from said path; a lever pressing on the disk to hold said lever from said path, and adapted to move into said notch, after a signal has been sent, thereby to move said lever into said path 10 and trap the key; releasing means to remove said lever from said path to permit the key to move and the clockwork to send another signal; and a stop pin on said control disk to engage said dog to stop the clockwork when 15 the key reaches releasing position.

9. In combination, a signal transmitter comprising a winding and unwinding arbor and a movable member; a control disk on said arbor provided with a notch; a pivoted dog 20 provided with a motive arm and with an active arm normally in the path of said member; a releasing pin on the control disk to engage said motive arm when the key reaches said limit, thereby to remove said active arm 25 from said path; a yieldable lever having a stop arm adapted to move into said path and a cam pressing on the control disk, thereby to hold said stop arm from said path, and adapted to move into said notch, after signals 30 have been sent, thereby to move said stop arm into said path and stop the clockwork with the key held trapped; releasing means to remove the stop arm from said path to permit the key to move the clockwork to send an 35 other signal; and a stop pin on said control disk to engage said motive arm to stop the clockwork when the key reaches releasing position.

10. In combination, a valve; a key-controlled lock for locking said valve and for releasing the key of the lock when said valve is locked in one position and trapping the key when said valve is not in said position; and signal means adapted to trap said key and 40 controlled by said key only, for giving a signal whenever the key is untrapped from said means.

11. In combination, a key-controlled lock adapted for releasing the key of said lock 45 when the bolt of lock is locked in one position and trapping the key when said bolt is not in said position; and signal means adapted to trap said key and controlled by said key only, for giving a signal when the key is untrapped from said means.

12. In combination, a key-controlled lock adapted for releasing the key of the lock when the bolt of said lock is locked in one position and trapping the key when said bolt is 50 not in said position, and signal means adapted to trap said key and controlled by the key only, for giving a signal when the key is being trapped in said means.

13. In combination, a key-controlled means 55 for releasing the key of said means, when

said means is locked in a certain position and trapping said key when said means is not in said certain position; and a signal means controlled by said key for trapping and releasing the key and giving one kind of signal when the key is trapped and another kind of signal whenever the key becomes released; the occurrence of the trapping signal and the failure of the occurrence of the releasing signal to occur positively indicating that said key-controlled means is locked in said certain position.

14. In combination, a key-controlled means for releasing the key of said means, when said means is locked in a certain position and trapping said key when said means is not in said certain position; and an intermittent-current code-signal means controlled by said key for trapping and releasing the key and positively indicating that said key-controlled means is locked in said certain position.

Signed at New York in the county of New York and State of New York this 10th day of November A. D. 1925.

JAMES G. NOLEN.
